VENTILATOR

Elias Kaplan, Hoboken, N. J., assignor to Elias Kaplan, Inc., a corporation of New Jersey

Application April 1, 1935, Serial No. 14,040

6 Claims. (Cl. 98—99)

This invention relates to improvements in ventilators and particularly window ventilators.

One of the objects of this invention is to provide a window ventilator for use in offices, homes and other places which avoids permanently-attached projecting parts, and comprises a body element and a holder member therefor, both of which are quickly and completely removable to enable the user speedily and effectively to completely free the window from all parts of the ventilating apparatus.

Another object of my invention is to provide a window ventilator of the type specified which will have a secure but readily-releasable connection at its middle portion with the middle of the window sill and is also provided with readily-releasable connection between the window sill and the opposite ends of the ventilator.

Another object of my invention is to produce a ventilator having at its edge vertically-disposed posts or pivots adapted to slidably fit into vertically-disposed sockets in a horizontal member of the window frame, such as the window sill, and preferably to turn therein.

Still another object of my invention is to provide a ventilator construction in which a ventilator body portion is slidably removable from holders therefor and the holders are slidably removable from the window.

Still another object of my invention is to enable a ventilator of the type hereinabove described to be utilized at the top of a window as well as at the bottom.

In general terms my invention comprises a means for mounting window ventilators which will avoid projections or defacement of the side window frame or sill, and will merely provide in the window sill at the corners adjacent to each of the sash grooves a vertical hole or aperture which is preferably metal lined and provides a pivot bearing for a pivot-element or post having connected thereto a holder for a ventilator body from which the latter may be readily removed. My invention also preferably provides at the center of the window sill a vertically disposed aperture, preferably lined, as aforesaid, and a pivot element or post adapted to function as a hinge pin to permit a ready swinging into the room or out of the window of hinged ventilator-body members.

My invention also contemplates the use of a construction in which the body of the ventilator may be composed of glass rods or glass strips and which may be independently removed from the

carrying member and may be swung about a hinge pin as hereinabove described.

With these and other objects in view, the invention comprises the combination of members and arrangement of parts so combined as to coact and co-operate with each other in the performance of the functions and the accomplishment of the results herein contemplated, and comprises in one of its adaptations the species or preferred form illustrated in the accompanying drawings, in which:

Fig. 1 is a view in front elevation of the lower portion of a window having mounted thereon ventilating apparatus embodying my invention applied to a double ventilator;

Fig. 2 is a view similar to Fig. 1 showing my invention applied to a single ventilator;

Fig. 3 is a section on the line 3—3 of Fig. 1 looking in the direction of the arrows;

Fig. 4 is a section on the line 4—4 of Fig. 1 looking in the direction of the arrows;

Fig. 5 is a view in perspective of a post and grooved carrier for the corners of a window sill;

Fig. 6 is a similar perspective of a post and carrier for the center of a window sill;

Fig. 7 is a fragmentary front elevation of a window having applied thereto a modified form of the apparatus in which the ventilating elements may be swung on the end posts acting as hinges;

Fig. 7a is a section on the line 7—7a of Fig. 7, looking in the direction of the arrows;

Fig. 8 is another modified form of my invention showing a removable carrier but omitting the post;

Fig. 9 is a view in perspective of a post employed at the corners in Fig. 8;

Fig. 10 is a view of a similar post and bracket which may be employed at the center of the window frame;

Fig. 11 is a fragmentary view of the lower portion of a window frame showing another modified form of my invention in which the post at the center constitutes a hinge to permit folding at the center;

Fig. 12 is another fragmentary view in front elevation of the lower portion of a window frame showing a modified form of my invention in which glass rods are utilized as the louvre portion of the ventilator;

Fig. 13 is a section on the line 13—13 of Fig. 12 looking in the direction of the arrows;

Fig. 14 is a section on the line 14—14 of Fig. 12 looking in the direction of the arrows;

Fig. 15 is a view similar to Fig. 14 showing a modified form of louvres;

Fig. 16 is still another section similar to Fig. 14 of a modified form of louvres, and

5 Fig. 17 is a fragmentary view of the top portion of a window frame showing a ventilator applied at the top.

Referring now to all the figures of these drawings, 1 indicates the sill of a window frame and 10 2, 2' the side rails thereof having sash-members 3 and inner and outer sash grooves 4, 4'.

In the preferred embodiment of my invention illustrated in Figs. 1 to 6 and 7 to 17, I provide on my ventilator 5 adjacent to the opposite ends 15 thereof and projecting from the edge thereof, posts or pivot members 6 which are readily removable from and preferably have a slideable connection with means on the window sill at the corners adjacent to the inner sash grooves 4 and 20 closely adjacent to the side frame members 2, 2', and I also preferably provide similar members 6 engageable with means at the center of the window sill. These pivot or post members 6 are 25 preferably slidably and rotatably mounted in vertically disposed sockets 7 formed in the window sill. In Fig. 1, three of these sockets 7 are shown, two of them being disposed adjacent to the sash grooves 4 of the inner sash 3 and the other being disposed at the center of the sill on the moulding 30 adjacent to the plane of the sash rail. The sockets 7 comprise vertical holes or bores made in the material of the sill or molding and preferably lined with metal tubes which are inserted therein so as to provide metal walled sockets or 35 pivot bearings 7 for the pivot members or posts 6.

In Figs 1 to 7a and 11, these posts have connected thereto grooved holders 8 for ventilator body element 9 which is provided with louvres 10 of conventional construction. In Figs. 7 and 40 7a the body element 9 is fastened to grooved holder members 8' and swings on the post members which form hinged pins for sections 9', 9^a of the louvred body element 9. In this construction, the meeting ends 9^b, 9^c of sections of the 45 body element 9 are adapted to swing inwardly into the room about the corner posts or pivots to enable access to the window without removal of the ventilator, and in closed position said ends engage a catch 10' on the window sill. 50 The meeting ends may, if desired, be swung outwardly of the window frame to function as air deflectors.

In Fig. 11 I have combined with corner posts 6 and corner holders 8, such as hereinabove described in relation to Figs. 1 to 7a, a central post 6' to which sections 9^d, 9^e of a louvred body element 9 are hinged. In this construction, the outer ends of the louvred body element may be 55 swung inwardly on the central hinge pin to permit temporary access to the window sash or frame without removal of the ventilator, or if desired, under suitable weather conditions may be swung outwardly to function as air deflectors for deflecting air from outside into the room.

65 In Figs. 12 to 16, I have shown a construction comprising two pairs of posts 6 each pair projecting from the bottom edge of a holder frame 11 composed of end members 12, 12' and a bottom member 13 connected together to produce a 70 grinding frame or pocket for a series of louvre-forming round bars 13 having central portions 13' reduced in diameter and end portions 13^a of increased dimensions so that when mounted in said frame, said bars will form between such 75 members ventilating slots or louvres 13^b.

In Fig. 15 I have illustrated straight strips 14 instead of round bars. In said Fig. 15 the ends 14^a are similarly of increased dimensions to provide slots 14' between the mounted strips.

In Fig. 16, I have shown similar strips 15 which are arranged obliquely to the end blocks 15' so as to enable upward deflection of the air by the outer surfaces 15^a as well as providing ventilating slots or louvres 15^b between the strips.

10 In Fig. 17, I have shown a construction in which the sections of the body element of the ventilator are made of metal and connected to post members 6^c and holders 8^c in a manner similar to that shown in Figs. 7—7a. In this construction, however, one end of each of the post members 6^c is provided with a screw thread 6^d and is screwed into the upper rail of a window frame instead of into the sill. These sections of the body element in this construction are also locked to the holder members by pins 16 so as to prevent dropping of the same by gravity. In other respects the construction is similar to that shown in Figs. 7 and 7a.

Having described my invention, I claim:

1. A ventilator for windows, comprising a pair of ventilator body elements, holders for engaging the edges of each member of said pair of body elements, located at the corners of the horizontal member of a window frame and at the middle 30 thereof, at least one of said edge holders being provided with a vertical post having a releasable sliding connection with said horizontal member of the window frame.

2. A ventilator for windows, comprising a ventilator body element having ventilating louvres, an edge-holder in which said body element is 35 removably mounted, and vertical post members and bearings therefor for removably mounting said edge-holder member, said post members and 40 bearings being connected with a horizontal member of the window frame at the corners of the window frame adjacent to the inner sash groove.

3. A ventilator for windows, comprising a ventilator body element having ventilating louvres, 45 an edge holder in which said body element is removably mounted, vertically disposed bearings connected with the window sill adjacent to the inner sash groove at the corners between horizontal and vertical members of the window frame 50 and vertical post members slidable in said bearings for mounting said edge-holders.

4. A ventilator for windows, comprising a ventilator body element having ventilating louvres, 55 an edge holder in which said body element is removably mounted, and composed of a frame member and a series of louvre-forming members mounted therein, vertically disposed bearings connected with the window sill adjacent to the inner sash groove at the corners between horizontal and vertical members of the window frame 60 and post members slidable in said bearings for mounting said edge-holders.

5. A ventilator for windows, comprising a ventilator body element having ventilating louvres, 65 and composed of a frame member and a series of louvre-forming members mounted therein, each comprising a narrow strip of glass having ends of increased dimensions to provide ventilating slots therebetween when mounted in said frame, an edge holder in which said body element is removably mounted, vertically disposed bearings connected with the window sill adjacent to the inner sash groove at the corners between horizontal and vertical members of the 70 frame, 75 and said bars will form between such members ventilating slots or louvres 13^b.

window frame and post members slidable in said bearings for mounting said edge-holders.

6. A ventilator for windows, comprising a ventilator body element having ventilating louvres, an edge-holder in which said body element is removably mounted, and vertically disposed post members and bearings therefor for removably mounting said edge-holder members, said post members and bearings being connected with a

horizontal member of the window frame at the corners of the window frame adjacent to the inner sash groove, said body element comprising two members foldable inwardly in relation to the window frame to enable access thereto without removing the ventilator and foldable outwardly in relation to the window frame to function as an air deflector. 5

ELIAS KAPLAN.
